A. E. NELSON

ORDER HOLDER FOR FILM HANGERS

Filed May 18, 1922

Patented Aug. 7, 1923.

1,464,157

UNITED STATES PATENT OFFICE.

ANDREW E. NELSON, OF MASON CITY, IOWA.

ORDER HOLDER FOR FILM HANGERS.

Application filed May 18, 1922. Serial No. 562,012.

To all whom it may concern:

Be it known that I, ANDREW E. NELSON, a citizen of the United States of America, residing at Mason City, in the county of Cerro Gordo and State of Iowa, have invented certain new and useful Improvements in Order Holders for Film Hangers, of which the following is a full, clear, and exact specification.

10 This invention relates to photography, and more particularly to photographic film handling racks which are used for holding film for treatment in the various baths and for drying. One object of my invention 15 is to provide an order holder for such a film rack. Another object is to provide an order holder which will keep the order dry during the film treatments. Another object is to provide a drainage channel between the order 20 holder and the film rack. Another object is to provide a plate to protect the order. Other objects will appear hereinafter from the specification, the novel feature being fully pointed out in the claims at the end of 25 the specification.

My present invention is particularly adapted for use with a film hanger of the type shown in Patent No. 1,089,916, Fisher, Mar. 10, 1914, and it is shown, by way of 30 illustration, as being applied to this hanger, although it is obvious that it is equally well suited to hangers which are hung in different positions for the various film treatments.

In the drawings, in which like reference 35 characters denote like parts throughout:

Fig. 1 is a perspective view of an order holder constructed in accordance with and illustrating one embodiment of my invention;

40 Fig. 2 is a side elevation thereof; and Fig. 3 is a detail perspective of the order holder in drainage position.

In this instance the hanger, as described in the Fisher patent, consists of two bars 1 and 2 hinged at one end by a link 3 and having at the opposite end a pin 4 on one bar co-operating with a keyhole slot 5 on the other bar to form a lock. There are at the last named end apertures 6, 6 in the 45 bars by which the hanger can be supported upon a rod R as is shown in Fig. 2, this being the drying position. The films F are supported by clasps 7, of which there are a series on each bar, pivoted to swing thereon 50 55 from the position shown in Fig. 1 to that of

Fig. 2. When the film is to be treated in the various baths, as for developing, fixing, washing, etc., the hanger is supported upon a rod R' which passes under the hook-like portion 15. If desirable to raise the hanger in the bath, the hanger may be supported by a rod R'' which passes between bars 1 and 2 beneath the link 3; so that for the baths the hanger is held in the position shown in Fig. 1.

I provide an order holder, here shown as a paper clip 8, pivoted at 9 to a plate 10, a portion of which 11 forms one jaw of the clip. A spring 12 encircling pintle 9 normally presses the jaws closed in a well known manner. The plate 10 is supported at an angle to the connecting plate 13 which may be riveted at 14 to one of the bars which carry the film clips, here shown as 1. This angular connection forms a drainage 75 channel 15 between the plate 10 and the supporting plate, as is best shown in Fig. 3, the object being to keep moisture from the order O which is held by the holder 8-11. It further provides a hook by which the hanger 80 may be suspended in the various baths.

The operation of my device is as follows: When film is received a clerk writes upon a numbered order blank O the necessary directions together with any other desirable 85 data. As the film F accompanying the order is placed in the clips 7 for treatment, the order is likewise placed in holder 8-11. The film is then treated in the necessary developing, fixing, washing and in any other 90 desirable baths, being supported from a rod R' or R'' in an upright position, as is shown in Fig. 1. After the final washing the hanger is reversed (Fig. 2) and hung up for drying upon a rod R, in which position 95 the films F extend from the sides of bars 1 and 2 due to the positions assumed by the clasps 7.

In the drying position water will drain down bars 1 and 2 and connecting plate 13. The water on side 16 of this plate will drain out through the channel 15 and drip from the sides, as is shown in Fig. 3. The plate 10 protects order O from water which may drip from the clasps 7, so that the jaws 8, 100 11 will always be kept dry and the order O held thereby will be protected from all moisture throughout the various steps in preparing the completed negatives.

I also contemplate providing the order 110

holders separate from the hangers, so that hangers now on the market can be equipped by simply attaching the connecting member to the hanger.

5 Having thus described my invention, what I claim as new and desire to secure by Letters Patent is:

1. In an order holder for film hangers, the combination of an order-engaging member, of a support having one end for carrying the order-engaging member, and the other end adapted to be fastened to a film hanger, and a bend in the support whereby the order-engaging member is held at an angle to that part of the support which is adapted to be fastened to the film hanger.
- 10 2. In an order holder for film hangers, the combination of an order-holding clip, of a supporting member, the clip being operatively connected to one end of the support, the other end of the support being adapted to be connected to a film hanger, and the intermediate portion of the support comprising a hook-shaped metal plate, whereby an order in the clip is held at an angle to that portion of the support adapted to engage the film hanger.
- 15 3. In a device for treating film, the combination with a film hanger adapted to be hung in different positions for the fluid treatment of film and for drying the film, of an order holder therefor, a support for the order holder having one end for carrying the holder and the other end for engaging the film hanger, means on the support for deflecting the drainage from the film hanger away from the order held by the holder when the hanger is positioned for drying the film.
- 20 40 4. In a device for treating film, the combination with a film hanger adapted to be hung in different positions for the fluid treatment of film and for drying the film,

of an order holder therefor, a support for the order holder comprising a flat plate bent between its ends to form a drainage channel, one end carrying the order holder, and the other end engaging the film hanger, whereby the drainage from the film hanger will drop from the drainage channel thus retaining the order held by the holder in a dry condition.

5. In a device for treating film in fluid baths and for drying film, the combination with a hanger adapted to be hung in one position for the fluid treatment and reversed for film drying, of an order holder, a bent support for the order holder connected to the hanger, a flat plate included in the support upon one side of which the order holder is mounted, the bent support forming a hook by which the hanger is supported for the fluid treatments and by which the order is held above the fluid, and when the hanger is reversed for drying, the bent support positions the order holder beneath the flat plate to one side of the drainage from the hanger.

6. In a device for treating film the combination with a film hanger adapted to be hung in one position for the treatment of the film in fluid, and in another position for the drying of the film, of an order holder, connections between the order holder and the film hanger including a bent member, this member serving as a hook for suspending the film hanger in its fluid-treating position and as a means for holding the order away from the drainage from the hanger when in its film-drying position, whereby the order will be held away from the fluid in both positions of the hanger.

Signed at Mason City, Iowa, this 12th day of May 1922.

ANDREW E. NELSON.
